REFRIGERATION

Arnold D. Siedle, Cleveland Heights, Ohio, assignor to The Hoover Company, North Canton, Ohio

Application June 25, 1941, Serial No. 399,630

30 Claims. (Cl. 62—119.5)

This invention relates to the art of refrigeration and more particularly to a novel three-fluid absorption refrigerating machine.

Previous absorption refrigerating machines present an extremely difficult problem of design to maintain the same within the rigid space limitations imposed upon commercially acceptable kitchen appliances. This arises from the fact that prior machines require the provision of a vertically extending cooling air flue along the back wall of the apparatus which consumes an appreciable quantity of the depth available for the apparatus. Previous machines are also at a considerable disadvantage because of the necessity of providing a heavy, cumbersome, rigid metal framework which will support the evaporator, condenser and rectifier at a height appreciably above the height at which the boiler-absorber and circulating fan are positioned. This frame must be very strong because the various parts of three-fluid refrigerating machines are very heavy.

Accordingly, it is an object of the present invention to provide a three-fluid absorption refrigerating apparatus in connection with a cabinet construction for housing the same which will totally eliminate the rear flue and will place all parts of the refrigerating apparatus within the projected area of the cabinet proper.

It is a further object of the present invention to provide a three-fluid air-cooled absorption refrigerating system in which the entire refrigerating mechanism excepting the evaporator and its connecting conduits is located within the confines of the cabinet walls beneath the food storage compartment in which the evaporator is positioned in the lower part of the storage compartment and is connected to the refrigerating mechanism *per se* by short direct conduit connections.

It is a further object of the present invention to provide an absorption refrigerating machine of the three-fluid type which is so constructed and arranged that the necessity for a heavy elongated supporting frame is totally eliminated.

It is a further object of the present invention to provide a three-fluid absorption refrigerating machine so constructed and arranged that this may be positioned beneath the food storage compartment and may be air cooled without the necessity of providing a flue structure along one vertically extending wall of the cabinet and without increasing the dimensions of the cabinet in any direction taken in a horizontal plane over those required to enclose the food storage space in an insulating wall.

It is a further object of the present invention to provide an absorption refrigerating apparatus of the type above described in which the air within the food storage compartment is circulated positively over the air cooling surfaces of the evaporator.

It is still another object of the present invention to provide an absorption refrigerating apparatus of the three-fluid type arranged for assembly in a domestic refrigerator cabinet which is characterized in that the same is extremely compact and has a minimum vertical height.

It is a further object of the present invention to provide a refrigerating apparatus so constructed and arranged that the entire operative mechanism may be completely assembled and tested in a low height assembly which includes the bottom portion of the cabinet and which may be assembled with the side, top, front and rear walls 10 of the refrigerating space by lowering the aforesaid walls of the refrigerated space over the assembled refrigerating mechanism and securing the two together.

It is a further object of the present invention 25 to provide an absorption refrigerating machine in which all portions of the operative refrigerating mechanism are located in the space below the food storage compartment and in the lower part of said compartment and in which the air cooled 30 condenser for the apparatus is placed within a pocket in the lower rear portion of a side wall of the apparatus which pocket is so arranged that no part of the apparatus projects beyond the horizontal dimensions of the cabinet proper.

It is a further object of the present invention 35 to provide a three-fluid absorption refrigerating machine in which all operative parts of the apparatus are located in the lower portion of and below the food storage compartment which are 40 so constructed and arranged that the same may be assembled with the cabinet simply by sliding the same into the cabinet construction from the rear thereof.

Other objects and advantages of the invention 45 will become apparent as the description proceeds when taken in connection with the accompanying drawings in which—

Figure 1 is a front elevational sectional view of one form of the invention;

Figure 2 is a side elevational view partly in section of the arrangement shown in Figure 1;

Figure 3 is a front sectional elevational view of a modified form of the invention;

Figure 4 is a side elevational view partly in section of the apparatus shown in Figure 3;

Figure 5 is a front elevational view partly in section of another modification of the invention; and

Figure 6 is a side elevational view partly in section of the apparatus illustrated in Figure 5.

In Figures 1, 3 and 5 certain heat rejecting fins have been omitted to clarify the drawings. These fins have been shown in companion Figures 2, 4 and 6, respectively.

Referring now to the drawings in detail and first to Figures 1 and 2 thereof, there is disclosed an absorption refrigerating apparatus of the three-fluid type associated with a suitable cabinet structure. Only the lower portion of the cabinet structure has been illustrated as the part thereof above the break line is simply a conventional cabinet structure to form a chamber for the storage of foodstuffs and the like to be refrigerated.

A three-fluid absorption refrigerating machine is associated with this cabinet construction and comprises a boiler B, an analyzer D, a tubular inclined air-cooled rectifier R, a tubular inclined air-cooled condenser C, an evaporator structure E, a horizontal multi-pass gas heat exchanger G, an inclined tubular air-cooled absorber A, a solution reservoir S, a liquid heat exchanger L, and a gas circulating fan or pump F which is driven by an electrical motor M. These elements are suitably interconnected by various conduits or the like to be described more fully hereinafter to form a plurality of gas and liquid circuits constituting a complete three-fluid absorption refrigerating machine.

The above described apparatus will be charged with a suitable refrigerant such as ammonia, a suitable solvent therefor, such as water and a pressure equalizing medium which is inert with respect to the refrigerant in the absorbent, preferably a dense gas like nitrogen.

A suitable control mechanism, not shown, will be provided to regulate the operation of the electrical motor M and the heater H which is arranged to supply heat to the boiler B. A preferred control mechanism is disclosed by Patent No. 2,228,343, dated January 14, 1941, issued to Curtis C. Coons.

In the normal operation of the system the boiler B contains a strong solution of refrigerant in the absorbent which liberates refrigerant vapor when heated. The vapor so liberated passes upwardly from the boiler through the analyzer D in counterflow relationship and in contact with solution flowing downwardly through the analyzer to the boiler. After passing through the analyzer the resulting refrigerant vapor is conveyed from the analyzer to the upper portion of the condenser C by means of the conduit 11 which has a finned section forming the air-cooled rectifier R.

The refrigerant vapor supplied to the condenser C is converted into the liquid state therein by heat exchange with cooling air flowing over the fins on the condenser. The resulting liquid refrigerant flows from the bottom portion of the condenser C through a conduit 12 to the bight portion of a U-shaped conduit 13 forming a twin gas lift elevating pump. Conduit 12 is vented to the gas heat exchanger G by a vent conduit 19. The lower portion of the conduit 13 is positioned at an elevation below the bottom portion of the condenser in order to insure that the same will be flooded with liquid and to provide an adequate

depth of immersion for the purpose of pumping the liquid to a higher level.

The gas lift pump 13 is actuated by pumping gas supplied to the upwardly extending legs 5 thereof by a U-shaped gas supply conduit 14 which receives pumping gas through a conduit 15 from the gas discharge conduit 16 of the circulating gas pump F. The gas introduced into the liquid in the legs of the conduit 13 elevates the same by gas lift action into a gas separation chamber 17 which is connected to the bottom portion of the evaporator E by means of a conduit 18.

The lean solution formed in the boiler by the 15 generation of refrigerant vapor is conveyed therefrom to the solution reservoir S by way of the conduit 20, the liquid heat exchanger L, and the conduit 21 which includes a finned air-cooled section which serves as a solution pre-cooler. 20 The reservoir S is vented by means of a conduit 22 to the suction conduit 23 of the circulating fan. The solution is conveyed from the reservoir S to the upper portion of the tubular absorber A adjacent its point of connection with the conduit 25 25 by means of a conduit 24 which connects to the bight portion of a U-shaped twin gas lift pump conduit 25. The bight portion of the conduit 25 is positioned below the liquid level normally maintained in the boiler-analyzer solution reservoir assembly in order to provide an operative depth of immersion for the gas lift pump.

Pumping gas is supplied to the vertically extending legs of the U-shaped conduit 25 from the 30 fan discharge conduit 16 by means of a conduit 26 and an inverted U-shaped conduit 27 which opens into the legs of the conduit 25, wherefore the absorbing solution is elevated from the reservoir into the absorber by gas lift action. Due to 40 the fact that the reservoir S is vented through the conduit 22 to the suction side of the circulating fan the entire pressure of the fan is available for operating the pump.

The absorbing solution which is supplied to the 45 upper end of the tubular absorber flows downwardly therethrough by gravity in counterflow relationship with a mixture of inert gas and refrigerant vapor which is supplied to the lower end of the absorber in a manner to be described hereinafter. The solution absorbs refrigerant vapor from the mixture and the resulting heat of absorption is rejected to cooling air flowing across the exterior walls of the absorber conduit and the fins mounted thereon.

The enriched solution which collects in the 50 lower part of the absorber is conveyed therefrom to the upper portion of the analyzer D by way of the conduit 28, the liquid heat exchanger L, and the conduit 29, thus completing the absorption solution circuit.

The circulating fan F receives lean pressure 55 equalizing medium from the absorber through the conduit 23, places the same under pressure and discharges the gas thus placed under pressure through the conduit 16 into the outer path of the gas heat exchanger G. As shown, the gas heat exchanger is a multi-pass baffled type which provides for considerable turbulence in the gas stream flowing therethrough and insures good heat exchange between the two streams of gas. After traversing the gas heat exchanger the inert gas is conveyed therefrom to the bottom portion of the evaporator E by way of conduit 31, gas separation chamber 17 and conduit 75 18.

The outer, lean gas pass of the gas heat exchanger has an appreciable resistance. This promotes heat transfer and provides an operative pressure differential for the gas lift pump 13 which in effect operates across the pressure drop in the gas in the lean gas side of the gas heat exchanger.

As illustrated, the evaporator E comprises an elongated conduit of relatively small diameter which is coiled to form three horizontally extending coil sections which are adapted to underlie and refrigerate ice tray supporting plates and which are serially connected by vertically extending riser conduits. This evaporator is of the general type disclosed and claimed in the co-pending application of Curtis C. Coons, Serial No. 386,394, filed April 2, 1941, now Patent No. 2,328,195, dated August 31, 1943.

This evaporator is of the type in which the inert gas and liquid refrigerant are both supplied to the bottom portion thereof and in which the inert gas circulates through the evaporator at a high velocity which is sufficient to circulate the liquid through the evaporator and to elevate the same upwardly between the various vertically spaced horizontal sections thereof by the frictional drag of the inert gas stream flowing over and through the liquid.

After traversing the evaporator the liquid is conveyed from the upper portion thereof by means of the conduit 33 to a vertically extending finned relatively large diameter evaporator coil 34. The liquid refrigerant flows downwardly through the coil 34 in parallel flow relationship with the inert gas. The inert gas and any unevaporated material are conveyed from the bottom portion of the coil 34 to the inner pass of the gas heat exchanger G by means of the conduit 35. The inert gas then passes through the inner path of the gas heat exchanger and is conveyed therefrom to the bottom portion of the absorber A by means of the conduit 36. The manner in which the inert gas refrigerant vapor mixture passes upwardly through the absorber in counterflow relationship with the absorbing solution has already been explained in connection with the absorbing solution circuit. This completes the inert gas circuit.

The gas heat exchanger G is provided with a conduit 37 connected between the end thereof which communicates with the conduit 35 and the lower portion of the absorber in order to drain the gas heat exchanger of any non-volatile material flowing thereinto from the evaporator.

The above described refrigerating apparatus is associated with a suitable cabinet construction 40 which includes an upper insulated food storage compartment 41 and a lower uninsulated mechanism compartment 42. The compartment 41 is provided with an insulated closure 43 and an insulated lower wall 44 which is removably connected to the vertically extending wall of the chamber 41 in a manner to be more fully described hereinafter.

The chamber 42 is formed within a base framework 45 which includes the wall 44 of the chamber 41. The bottom portion of the base framework is open to allow free flow of cooling air thereinto from the floor level as is indicated in Figures 1 and 2. The rear and side edges of the insulated plate element 44 are stepped as indicated at 46 to cooperate with complementary steps 47 formed on the lower ends of the side and rear walls of the compartment 41.

This forms a secure seat for the walls of the

refrigerated chamber and insures that the same will register properly. If desired, suitable gasket material, not shown, may be inserted in this joint to insure that the same will be air-tight.

5 The front edge 48 of the plate 44 is formed to cooperate with the closure 43 of the compartment 41. The wall 44 may be suitably secured to the rear and side walls of the chamber 41 by bolts, clips, stays or the like, not shown.

10 The boiler assembly, solution reservoir, boiler heater motor fan unit, absorber, condenser and rectifier are supported in the chamber 42 by a box frame 49, only a portion of which is shown. It will be understood that this box frame will include vertically extending elements to which the absorber, motor circulator and the like will be suitably secured as by welding either directly or by welding short supporting rods to the frame and to the supported element. The boiler absorber liquid heat exchanger assembly is encased in a blanket of insulating material indicated at 51 and simply rests upon the bottom of the frame 49 to which of course it is suitably secured as by welding or the like.

15 20 25 It may readily be seen from an inspection of Figures 1 and 2 the absorber is positioned in the front portion of the chamber 42 and inclined downwardly and rearwardly therein. The condenser is positioned at a slightly higher elevation in the

30 35 40 upper rear portion of the chamber 42 and inclined downwardly and rearwardly therein. It will be understood that the individual condenser and absorber tubes are inclined with respect to each other as well as generally inclined downwardly in order to provide downward liquid flow in each case. Cooling air enters the bottom portion of the chamber 42, flows substantially vertically across the absorber and condenser and then exits from the chamber 42 through the opening 52 in the rear wall thereof. However, if desired, suitable openings or louvres may also be provided in the side walls of the chamber 42.

45 50 The boiler is provided with a waste products of combustion flue 53, shown broken, which will be provided with a suitable outlet to the opening 52 but to one side of the outlet for the condenser and absorber cooling air in order not to cause interference between the cooling air for the absorber and condenser and the waste products of combustion.

The gas heat exchanger G, as is seen in Figures 1 and 2, is embedded in the insulation of the plate 44.

55 60 65 The freezing evaporator E is positioned in the lower left hand corner of the chamber 41, as is shown in Figure 1. This evaporator is encased in a suitable housing 59 which will conceal the coil 32 and the tray supporting shelves, ice trays and the like. The air cooling evaporator 34 is positioned along the right hand wall, as viewed in Figure 1, of the compartment 41 in the lower part thereof and is separated from the remaining portion of the compartment 41 by a vertically extending plate or partition 50 which, however, terminates short of the bottom wall of the compartment 41 in order to allow air to enter the channel or flue housing the coil 34.

70 75 Positive air circulation across the air cooling coil and through the food storage compartment is provided by means of a propeller blade fan 54 which is positioned adjacent the panel 44 beneath the coils 34 and about midway between the front and rear walls of the compartment 41 adjacent the right hand wall thereof, as viewed in Figure 1. The fan 54 is driven by a suitable

electrical motor 55 which is partially embedded in the lower side of the panel 44 and is connected to the fan by means of a shaft 56 which passes through the panel 44. Thus, rotation of the fan blades 54 circulates air upwardly between the partition 50 and the adjacent side wall of the chamber 41 across the evaporator coil 34 and its associated fins. This provides positive circulation of the air within the compartment 41.

Electrical energy is supplied to the electrical motor 55 by the electrical conductors 57 which include the thermostat 58 positioned to be responsive to the temperature of the air within the chamber 41. The thermostat 58 is so constructed and arranged that the same will energize the motor 55 when the temperature of the air within the compartment 41 exceeds a predetermined value and will de-energize the motor 55 when the temperature of the air within said compartment drops below another predetermined value. Thus, the apparatus is arranged to maintain the temperature within the food storage space 41 within desired limits.

In assembling the apparatus the entire refrigerating mechanism is assembled together with the frame 49, the base structure 45 and the walls of the compartment 42 and the panel 44. This assembly will include the evaporators, their connecting conduits and the air circulating fan and motor. This apparatus may then be tested in this condition. After complete assembly of this apparatus the cabinet 40 is then swung over the aforesaid assembly and is lowered into position upon the stepped shoulders formed on the edges of the panel 44 after which the upper cabinet construction is suitably secured to the lower mechanism assembly and the apparatus is completed.

This assembly and construction totally eliminates the rear flue customarily provided in refrigerating systems of this type wherefore with this construction absorption refrigerating machine cabinets and the like may be made in standard sizes which do not exceed the permissible depth of kitchen appliances while providing standard depth within the food storage compartment. The apparatus is much more compact than prior constructions and results in a very appreciable saving in weight and in fabrication costs. Another feature of considerable advantage possessed by the instant construction results from the fact that the apparatus does not require the usual heavy elongated supporting frame which extends upwardly along the back wall of the cabinet in the usual cooling air flue.

It is characteristic of this invention that all the mechanism lies within the projected area of the normal food storage compartment and its normal surrounding wall, nothing projects there beyond. It is also characteristic of this form of the invention that the condenser is positioned in the mechanism compartment along with the absorber, boiler and circulator assembly and that the liquid refrigerant is positively elevated from the condenser to the bottom portion of the evaporator through which it is upwardly propelled by the inert gas as it is evaporating. This construction greatly promotes a compactness of assembly of the apparatus and efficiency of operation thereof.

Referring now to Figures 3 and 4, there is disclosed a modified form of the invention. Certain parts of this form of the invention are identical with parts of the form of the invention described in connection with Figures 1 and 2, and they are

therefore given the same reference characters primed.

In this form of the invention, the cabinet 40' is provided with a rear wall 60 which is provided with an inwardly formed recess 61 which receives the condenser C' and a part of the vertically extending rectifier R'. Consequently, in this form of the invention the vapor conduit 11' extends from the analyzer D' to the upper portion of the condenser C' which lies within the recess 61.

The solution circuit in this form of the invention is identical in all respects with the solution circuit described in connection with Figures 1 and 2 and need not be further described herein.

The inert gas circuit in this form of the invention is also identical with the inert gas circuit described in connection with Figures 1 and 2, except that the liquid refrigerant is supplied, in a manner to be described hereinafter, to the evaporator without the operation of a gas lift pump and the evaporator sections are arranged differently in the cabinet though the parts thereof are identical with the parts of the evaporator described in connection with Figures 1 and 2.

The liquid refrigerant is conveyed from the bottom portion of the condenser to the conduit 31' which conveys inert gas from the gas heat exchanger into the bottom portion of the evaporator E by means of the conduit 62 which includes a downwardly extending U-shaped portion. The liquid refrigerant flows through this conduit by gravity but a pressure-balancing liquid seal is provided in the condenser side of the U-shaped conduit in order to compensate for the difference in pressure existing between the conduit 31' and the condenser C'. The condenser side of the conduit 62 is subject to the rich gas side of the gas heat exchanger G' by means of a vent conduit 63.

The panel 44' of the cabinet 40' is identical with the panel 44 described in connection with Figures 1 and 2, with the exception that the rear edge thereof terminates short of the rearmost side of the cabinet in order to receive the inwardly recessed portion of the cabinet wall 60 which is set in to form the recess 61.

Referring particularly to Figure 3, it will be seen that the evaporator in this form of the invention is arranged somewhat differently from the arrangement disclosed in Figures 1 and 2. In the present form of the invention, the evaporator E' is positioned slightly to the right, as viewed in Figure 3, of the bottom central portion 55 of the chamber 41' and the finned air-cooling portion of the evaporator is positioned in the narrow flue-like space provided between the right, as viewed in Figure 3, wall of the cabinet 40' and the adjacent side wall of the evaporator casing, thus tending to form a vertically extending flue for cooling air so arranged that the propeller blade fan 54' will project the air upwardly across the cooling evaporator 34'.

This form of the invention is assembled exactly in the manner described in connection with the form of the invention disclosed in Figures 1 and 2. The cabinet 40' is simply lowered downwardly over the bottom mechanism assembly until the shoulders 46' and 47 engage after which the two parts of the cabinet are suitably secured together.

In this form of the invention the gas lift pump and the separation chamber between the evaporator and condenser are eliminated and the liquid refrigerant is supplied to the bottom por-

tion of the evaporator by gravity. The arrangement of the condenser in a rear pocket slightly decreases the available space within the food storage compartment but it improves the cooling efficiency of the system as the condenser and absorber are cooled by entirely separate and distinct air streams in this form of the invention, also the mechanism compartment underlying the storage chamber is less complex than in the form of the invention disclosed in connection with Figures 1 to 3.

It is characteristic of this form of the invention, however, like that described in connection with Figures 1 and 2, that the entire apparatus is positioned within the horizontal projected area of the normal storage space of the refrigerator compartment wherefore the need for a rear air flue, a heavy frame extending therealong and the like are totally eliminated from the machine without impairing its efficiency and without materially reducing the storage space in the cabinet. Also the evaporator arrangement of this form of the invention is more compact than that disclosed in connection with Figures 1 and 2.

Referring now to Figures 5 and 6, there is disclosed a third form of the invention. Many parts of this form of the invention are identical with parts heretofore described in detail in connection with Figures 1 and 2 and they are therefore given the same reference characters double primed. This form of the invention differs from the forms of the invention described heretofore in the arrangement of the evaporator, circulating fan and gas heat exchanger with respect to the cabinet, in the manner in which the mechanism is assembled with the cabinet and in a few details of construction.

The absorbing solution circuit is identical in all respects with the form of the invention illustrated in Figure 1.

Likewise, the inert gas circuit is identical in all respects with the form of the invention illustrated in connection with Figure 1, except as to the location of certain parts which will be described in detail hereinafter.

In this form of the invention, the cabinet 40' includes a lower wall structure 66 which is part of the cabinet structure proper and is provided with an opening 67 in its rear wall which is designed to be closed by an insulated panel element 68. A suitable gasket 69 is provided to seal the joint between the rear wall and the panel 68.

The refrigerating apparatus, in this form of the invention is slid into the cabinet from the rear through the rear wall of the mechanism compartment 42' and the opening 67 in the rear wall of the cabinet construction. It will be understood that in this form of the invention, the base, the walls of the mechanism chamber and the base plate are part of the cabinet assembly and not a part of the refrigerating mechanism assembly as in the forms of the invention previously described.

In this form of the invention also the gas heat exchanger G' is positioned in the rear, upper corner of the mechanism compartment 42'.

The liquid refrigerant discharging from the bottom portion of the condenser C' flows through a conduit 10 into the bight portion of a U-shaped gas lift pumping conduit 71, the vertically extending legs of which discharge into a separation chamber 17' which is positioned in the insulation of the panel element 68. Pumping gas is supplied to the vertically extending legs 75

of the twin gas lift pump 71 by means of conduits 15" and 14" whereby to elevate the liquid refrigerant by gas lift action into the separation chamber.

5 The liquid refrigerant and inert gas pass from the chamber 17' into the bottom portion of the evaporator E' through the conduit 18' through which the liquid refrigerant is propelled by the gas stream. The liquid refrigerant is propelled upwardly through the evaporator E' by the high velocity gas stream in the manner described in connection with the evaporators E and E'. The air cooling evaporator 34', in this form of the invention, is positioned directly behind the evaporator E' and its associated casing, and it will be noted that the evaporator E' is positioned in the bottom central portion of the food storage compartment 41'.

10 The evaporator 34' is provided with the usual vertically extended fins which are positioned in a vertically extended air channel, one side of which is formed by the rear wall of the casing of the evaporator E' and the other side of which is formed by a vertically extending panel 14 which extends from a point adjacent the upper ends of the fins to the bottom thereof. The fins terminate above the bottom wall of the compartment 41'. A second vertically extending channel is provided between the rear face of the panel 14 and a panel 18. The upper end of this channel is closed by a short panel 72 and the bottom end of both channels is closed by a panel 73. The panel 18 is spaced from the inner face of the closure plate 68 and is provided with an opening 75 which is positioned adjacent the central portion of a centrifugal fan 76 which is driven by an electrical motor 77 which is embedded in the insulation of the panel 68.

15 As may readily be seen from Figure 6, the air in the compartment 41' passes downwardly across the evaporator conduit 34 and its associated fins rearwardly under the lower edge of panel 14, upwardly in the channel between panels 14 and 18, through the opening 75 into the central portion of the centrifugal fan 76 from which it is discharged upwardly through a passageway formed between the panel 68 and the plate 78. Therefore, the air within the food storage compartment 41' is positively circulated by the circulating fan 76. It will be understood that the motor 77 will be controlled in exactly the same manner as the motor 55, described in connection with Figure 1, is operated and controlled.

20 In this form of the invention all parts to be operated, as well as the gas heat exchanger and rectifier, are positioned beneath the panel 66 of the compartment 41' and the cooling air discharged through the rear wall of the mechanism compartment 42'. In assembling the apparatus, the frame structure 49' is assembled with the entire refrigerating mechanism, and will include, of course, the panel 68 and its associated electrical motor; and it will also include the evaporators and the panels provided to form the air circulation current. When this apparatus is completely assembled, it will be slid into the cabinet structure from the rear thereof which will position the boiler assembly, absorber, solution reservoir, rectifier, gas heat exchanger and condenser in the lower mechanism compartment 42' beneath the panel 66, will position the panel 68 in the opening 67 in the rear portion of the food storage compartment, and will position the evaporator and its associated air directing struc-

ture within the bottom portion of the food storage compartment.

This form of the invention, like those described heretofore, insures that all portions of the apparatus will be maintained within the projected area of the normal dimensions of the food storage compartment and it completely eliminates the necessity for a vertical flue and for a heavy, space consuming metal supporting frame extending upwardly along the rear wall of the cabinet construction; thus materially reducing waste material and space consumption.

This form of the invention, however, is particularly designed for incorporation in cabinets which are to be used in environments in which it is not feasible to assemble the apparatus by dropping the cabinet construction downwardly over the mechanism.

All forms of the present invention greatly reduce the space occupied by the mechanical portions of absorption refrigerating machines compared to prior constructions. The assembly of the apparatus with the cabinet is materially simplified. In addition, the present invention provides a novel arrangement of evaporator and condenser which permits the condenser to be placed at an elevation below the evaporator and to be positioned within the mechanism compartment customarily provided in the cabinet beneath the food storage compartment. This is a construction and arrangement which is a radical departure from previous constructions.

While the invention has been illustrated and described herein in considerable detail, it is not to be limited to the constructional details illustrated and described. Various changes in construction, arrangement and proportion of the parts may be made without departing from the spirit of the invention or the scope of the appended claims.

I claim:

1. In a refrigerator, a cabinet having an insulated food compartment and a mechanism chamber arranged for flow of cooling air therethrough and entirely positioned below said food compartment, an absorption refrigerating mechanism associated with said cabinet including an evaporator in said compartment, an air cooled condenser and an air cooled absorber in said chamber, a boiler assembly in said chamber, means connecting said absorber and said boiler assembly for circulation of absorption solution, means connecting said absorber and said evaporator for circulation of inert gas, and means for conducting refrigerant vapor from said boiler assembly to said condenser and for conducting refrigerant liquid from said condenser to said evaporator.

2. In a refrigerator, a cabinet having an insulated food compartment and an underlying mechanism chamber arranged for flow of cooling air therethrough, an absorption refrigerating mechanism associated with said cabinet including an evaporator in said compartment, an air cooled condenser positioned in a recess formed in a vertical wall of said compartment, an air cooled absorber and a boiler assembly in said chamber, means connecting said absorber and said boiler assembly for circulation of absorption solution, means connecting said absorber and said evaporator for circulation of inert gas, and means for conducting refrigerant vapor from said boiler assembly to said condenser and for conducting refrigerant liquid from said condenser to said evaporator.

3. In a refrigerator, a cabinet including structure forming an insulated food compartment and an underlying mechanism chamber arranged for flow of cooling air therethrough, an absorption refrigerating mechanism associated with said cabinet including an evaporator in said compartment, an air cooled condenser, an air cooled absorber and a boiler assembly in said chamber, means connecting said absorber and said boiler assembly for circulation of absorption solution, means connecting said absorber and said evaporator for circulation of inert gas, and means for conducting refrigerant vapor from said boiler assembly to said condenser and for conducting refrigerant liquid from said condenser to said evaporator, all of said refrigerating mechanism being within the vertical projection of the horizontal dimensions of said structure forming said food compartment.

4. In a refrigerator, a cabinet including structure forming an insulated food compartment and an underlying mechanism chamber arranged for flow of cooling air therethrough, an absorption refrigerating mechanism associated with said cabinet including an evaporator positioned in the lower part of said compartment and including freezing and air cooling sections, a condenser, an air cooled absorber and a boiler assembly in said chamber, means connecting said absorber and said boiler assembly for circulation of absorption solution, means connecting said absorber and said evaporator for circulation of inert gas, and means for conducting refrigerant vapor from said boiler assembly to said condenser and for conducting refrigerant liquid from said condenser to said evaporator, all of said refrigerating mechanism being within the vertical projection of the horizontal dimensions of said structure forming said food compartment.

5. In a refrigerator, a cabinet including an open bottomed insulated element adapted to form the side and top walls of an insulated refrigerating chamber and a base and mechanism element removably supporting said first mentioned element and including an insulated panel arranged to interfit with said first mentioned element to form the lower wall thereof, a refrigerating mechanism associated with said base element including an evaporator positioned above said insulated panel, an air cooled condenser positioned within the horizontal dimensions of said first mentioned element, an air cooled absorber and a boiler assembly positioned below said insulated panel, and means connecting said evaporator, said absorber, said condenser and said boiler assembly to form a refrigerant circuit, said base element being constructed and arranged to support said refrigerating mechanism and said first mentioned element.

6. In a refrigerator, a cabinet including an open bottomed insulated element adapted to form the side and top walls of an insulated refrigerating chamber and a base and mechanism element removably supporting said first mentioned element and including an insulated panel arranged to interfit with said first mentioned element to form the lower wall thereof, a refrigerating mechanism associated with said base element including an evaporator having freezing and air cooling portions positioned above said insulated panel, an air circulating fan arranged to circulate air over said air cooling evaporator portion, a drive motor for said fan positioned outside said refrigerating chamber and partially embedded in a wall thereof, an air cooled condenser

positioned within the horizontal dimensions of said first mentioned element, an air cooled absorber and a boiler assembly positioned below said insulated panel, and means connecting said evaporator, said absorber, said condenser and said boiler assembly to form a refrigerant circuit, said base element being constructed and arranged to support said refrigerating mechanism and said first mentioned element.

7. In a refrigerator, a cabinet including an open bottomed insulated element adapted to form the side and top walls of an insulated refrigerating chamber and a base and mechanism element removably supporting said first mentioned element and including an insulated panel arranged to interfit with said first mentioned element to form the lower wall thereof, a refrigerating mechanism associated with said base element including an evaporator having freezing and air cooling portions positioned above said insulated panel, means forming an air passage-way across said air cooling portion of said evaporator, an air circulating fan arranged to circulate air over said air cooling evaporator portion, a drive motor for said fan positioned outside said refrigerating chamber and partially embedded in a wall thereof, an air cooled condenser positioned within the horizontal dimensions of said first mentioned element, an air cooled absorber and a boiler assembly positioned below said insulated panel, and means connecting said evaporator, said absorber, said condenser and said boiler assembly to form a refrigerant circuit, said base element being constructed and arranged to support said refrigerating mechanism and said first mentioned element.

8. In a refrigerator, a cabinet structure having an insulated food compartment and a mechanism chamber beneath said food compartment and arranged for flow of cooling air therethrough, an absorption refrigerating mechanism associated with said cabinet including an evaporator in said compartment, an air cooled condenser positioned in said cabinet within the vertical projection of the horizontal dimensions of said food compartment structure, an air cooled absorber and a boiler assembly arranged in said mechanism compartment, means providing for circulation of inert gas between said evaporator and said absorber, means providing for circulation of absorption solution between said absorber and said boiler assembly, means for conducting refrigerant vapor from said boiler assembly to said condenser, means including a gas lift pump for conveying refrigerant liquid from said condenser to said evaporator, and means for introducing pumping gas into said gas lift pump.

9. In a refrigerator, a cabinet structure having an insulated food compartment and a mechanism chamber beneath said food compartment and arranged for flow of cooling air therethrough, an absorption refrigerating mechanism associated with said cabinet including an evaporator in said compartment, an air cooled condenser positioned in said cabinet within the vertical projection of the horizontal dimensions of said food compartment structure, an air cooled absorber and a boiler assembly arranged in said mechanism compartment, means providing for circulation of inert gas between said evaporator and said absorber, means providing for circulation of absorption solution between said absorber and said boiler assembly, means for conducting refrigerant vapor from said boiler assembly to said condenser, means including a gas lift pump for conveying

refrigerant liquid from said condenser to said evaporator, and means for introducing pumping gas into said gas lift pump, said evaporator being so constructed and arranged that the refrigerant liquid is positively propelled therethrough by the inert gas.

10. In a refrigerator, a cabinet structure having a lower mechanism compartment arranged for circulation of cooling air therethrough and an insulated refrigerating compartment having an evaporator receiving opening in the lower part of a vertical wall thereof above said mechanism compartment, an insulated closure element for said opening, absorption refrigerating apparatus associated with said cabinet structure comprising an evaporator positioned adjacent the lower wall of said refrigerating compartment, an air cooled absorber and a boiler assembly in said mechanism compartment connected for circulation of absorption solution, an inclined air cooled condenser in said mechanism compartment arranged to receive refrigerant vapor from said boiler assembly and to supply refrigerant liquid to said evaporator, and means providing for circulation of inert gas between said evaporator and said absorber.

11. In a refrigerator, a cabinet structure having a lower mechanism compartment arranged for circulation of cooling air therethrough and an insulated refrigerating compartment having an evaporator receiving opening in the lower part of a vertical wall thereof above said mechanism compartment, an insulated closure element for said opening, absorption refrigerating apparatus associated with said cabinet structure comprising an evaporator positioned adjacent the lower wall of said refrigerating compartment, an air cooled absorber and a boiler assembly in said mechanism compartment connected for circulation of absorption solution, an inclined air cooled condenser in said mechanism compartment arranged to receive refrigerant vapor from said boiler assembly and to supply refrigerant liquid to said evaporator, and means providing for circulation of inert gas between said evaporator and said absorber including a gas heat exchange element positioned in said mechanism compartment.

12. In a refrigerator, a cabinet structure having a lower mechanism compartment arranged for circulation of cooling air therethrough and an insulated refrigerating compartment having an evaporator receiving opening in the lower part of a vertical wall thereof above said mechanism compartment, an insulated closure element for said opening, a blower for positively circulating the air in said refrigerating compartment, a drive motor for said blower embedded in the insulation of said closure element, absorption refrigerating apparatus associated with said cabinet structure comprising an evaporator positioned adjacent the lower wall of said refrigerating compartment, an air cooled absorber and a boiler assembly in said mechanism compartment connected for circulation of absorption solution, an inclined air cooled condenser in said mechanism compartment arranged to receive refrigerant vapor from said boiler assembly and to supply refrigerant liquid to said evaporator, and means providing for circulation of inert gas between said evaporator and said absorber including a gas heat exchange element positioned in said mechanism compartment.

13. In a refrigerator, a cabinet structure having a lower mechanism compartment arranged for circulation of cooling air therethrough and an insulated refrigerating compartment having an

evaporator receiving opening in the lower part of a vertical wall thereof above said mechanism compartment, an insulated closure element for said opening, a rigid frame structure positioned in said mechanism compartment, an absorption refrigerating apparatus associated with said cabinet and supported on said frame structure comprising an air cooled absorber and a boiler assembly mounted on said frame and connected for circulation of absorption solution, an air cooled condenser supported on said frame and connected to receive refrigerant vapor from said boiler assembly, an evaporator positioned above said frame in said refrigerating compartment, means connecting said evaporator and said absorber for circulation of inert gas therebetween, and means for conveying refrigerant liquid from said condenser to said evaporator, said frame, said refrigerating mechanism and said closure element forming a rigid assembly which is assembled with 10 said cabinet by sliding the said rigid assembly into said cabinet structure.

14. In a refrigerator, a cabinet structure having a lower mechanism compartment arranged for circulation of cooling air therethrough and an insulated refrigerating compartment having an evaporator receiving opening in the lower part of a vertical wall thereof above said mechanism compartment, an insulated closure element for said opening, a rigid frame structure positioned in said mechanism compartment, an absorption refrigerating apparatus associated with said cabinet and supported on said frame structure comprising an air cooled absorber and a boiler assembly mounted on said frame and connected for circulation of absorption solution, an air cooled condenser supported on said frame and connected to receive refrigerant vapor from said boiler assembly, an evaporator having a freezing section and an air cooling section positioned rearwardly of said freezing section, said evaporator being positioned above said frame in said refrigerating compartment, means connecting said evaporator and said absorber for circulation of inert gas therebetween, means for conveying refrigerant liquid from said condenser to said evaporator, means forming a conduit system arranged for circulation of air from said refrigerating compartment over said air cooling evaporator and back to said compartment, a blower for circulating air through said conduit system and a drive motor for said blower embedded in the insulation of said closure element, said frame, said refrigerating mechanism and said closure element forming a rigid assembly which is assembled with said cabinet by sliding the said rigid assembly into said cabinet structure.

15. Refrigerating apparatus comprising a cabinet structure having an insulated refrigerating chamber and a mechanism compartment entirely underlying said refrigerating chamber, a refrigerating mechanism of the three-fluid absorption type associated with said cabinet structure including an evaporator in said chamber, a boiler in said compartment, an air cooled absorber and an air cooled condenser in said compartment, and means for positively elevating refrigerant liquid from said condenser upwardly to said evaporator.

16. Refrigerating apparatus comprising a cabinet structure having an insulated refrigerating chamber and an underlying mechanism compartment, a refrigerating mechanism of the three-fluid absorption type associated with said cabinet structure including an evaporator in said

chamber, a boiler in said compartment, an air cooled absorber and an air cooled condenser in said compartment, a gas heat exchanger embedded in the insulation of the bottom wall of said compartment, and means for positively elevating refrigerant liquid from said condenser upwardly to said evaporator.

17. Refrigerating apparatus comprising a cabinet structure having an insulated refrigerating chamber and an underlying mechanism compartment, a refrigerating mechanism of the three-fluid absorption type associated with said cabinet structure including an evaporator in said chamber, a boiler in said compartment, an air cooled absorber in said compartment, an air cooled condenser positioned in a recess in a wall of said chamber of such dimensions that no part of said condenser projects beyond the normal wall limits of said chamber, and means for conveying refrigerant liquid by gravity from said condenser to said evaporator, said recess being so constructed and arranged that cooling air may flow therethrough across said condenser and said mechanism compartment being constructed and arranged for circulation of cooling air in contact with said absorber.

18. Refrigerating apparatus comprising a cabinet structure having an insulated refrigerating chamber and a mechanism compartment below and within the vertical projection of the horizontal dimensions of said refrigerating chamber, a refrigerating mechanism of the three-fluid absorption type associated with said cabinet structure including an evaporator in said chamber, a boiler in the bottom part of said compartment, a tubular finned multi-pass absorber conduit positioned in the upper front portion of said compartment and inclined generally downwardly and rearwardly to provide for gravity flow of solution therethrough, a tubular finned multi-pass condenser conduit positioned in the upper rear portion of said mechanism compartment and inclined generally downwardly and rearwardly to provide for gravity flow of refrigerant liquid to the lower part thereof, and means connecting said boiler, said condenser, said evaporator and said absorber for circulation of refrigerant, said cabinet structure being arranged to provide for flow of cooling air into the lower part of said mechanism compartment and for discharge to the surrounding atmosphere of air heated by said absorber and said condenser.

19. Refrigerating apparatus comprising a cabinet structure having an insulated refrigerating chamber and an underlying mechanism compartment, a refrigerating mechanism of the three-fluid absorption type associated with said cabinet structure including an evaporator in said chamber, a boiler in the bottom part of said compartment, a tubular finned multi-pass absorber conduit positioned in the upper front portion of said compartment and inclined generally downwardly and rearwardly to provide for gravity flow of solution therethrough, a tubular finned multi-pass condenser conduit positioned in the upper rear portion of said mechanism compartment and inclined generally downwardly and rearwardly to provide for gravity flow of refrigerant liquid to the lower part thereof, a power driven gas circulator assembly positioned in said compartment, and means connecting said boiler, said condenser, said gas circulator assembly, said evaporator and said absorber for circulation of refrigerant, said cabinet structure being arranged to provide for flow of cooling air into the

lower part of said mechanism compartment and for discharge to the surrounding atmosphere of air heated by said absorber and said condenser, and said gas circulator assembly being positioned out of the path of flow of air traversing said condenser and said absorber.

20. In a refrigerator, structure forming an insulated food preserving compartment, structure forming a mechanism chamber underlying and supporting said compartment, a three-fluid refrigerating apparatus associated with said compartment and said chamber comprising an evaporator in said compartment, a tubular air cooled absorber in said chamber, a tubular air cooled condenser, a generator in said chamber, means providing for circulation of inert gas between said absorber and said evaporator including a power driven device for elevating the pressure of the inert gas to cause the gas to circulate, means providing for circulation of absorption solution between said generator and said absorber including means operated by inert gas at the elevated pressure for elevating absorption solution between the generator and the absorber, means for conducting refrigerant vapor evolved in said generator to said condenser, and means for conducting refrigerant liquid from said condenser to said evaporator, said apparatus being characterized by the fact that all portions thereof lie within the horizontal dimensions of said structure forming said compartment and below the upper wall thereof.

21. In a refrigerator, structure forming an insulated food preserving compartment, structure forming a mechanism chamber underlying and supporting said compartment, a three-fluid refrigerating apparatus associated with said compartment and said chamber comprising an evaporator in said compartment, a tubular air cooled absorber in said chamber, a tubular air cooled condenser, a generator in said chamber, means for conducting refrigerant vapor from said generator to said condenser, means for conducting refrigerant liquid from said condenser to the lower portion of said evaporator, means providing for circulation of inert gas between said absorber and said evaporator including a power driven device for imparting sufficient pressure and velocity to the inert gas to cause the inert gas to circulate refrigerant liquid upwardly through said evaporator, and means providing for circulation of absorption solution between said generator and said absorber including means operated by inert gas under pressure for elevating absorption solution between the generator and the absorber, said apparatus being characterized by the fact that all portions thereof lie within the horizontal dimensions of said structure forming said compartment and below the upper wall thereof.

22. In a refrigerator, a cabinet structure including an insulated food compartment and a mechanism chamber arranged for flow of cooling air therethrough, an absorption refrigerating apparatus associated with said cabinet structure including an evaporator in said compartment, an air cooled absorber and an air-cooled condenser in said chamber below said food compartment, a generator in said chamber, means providing for circulation of inert gas between said absorber and said evaporator, means providing for circulation of absorption solution between said absorber and said generator, means for conveying refrigerant vapor from said generator to said condenser, and means for conveying refrigerant liquid upwardly from said condenser to said evaporator.

23. In a refrigerator, a cabinet structure including an insulated food compartment and a mechanism chamber arranged for flow of cooling air therethrough, an absorption refrigerating apparatus associated with said cabinet structure including an evaporator in the lower part of said compartment, an air cooled absorber and an air cooled condenser in said chamber below said food compartment, a generator in said chamber, means providing for circulation of inert gas between said absorber and said evaporator, means providing for circulation of absorption solution between said absorber and said generator, means for conveying refrigerant vapor from said generator to said condenser, and means for conveying refrigerant liquid upwardly from said condenser to said evaporator.

24. In a refrigerator, a cabinet structure including an insulated food compartment and a mechanism chamber arranged for flow of cooling air therethrough, an absorption refrigerating apparatus associated with said cabinet structure including an evaporator in the lower part of said compartment, an air cooled absorber and an air cooled condenser in said chamber below said food compartment, a generator in said chamber, means providing for circulation of inert gas between said absorber and said evaporator, means providing for circulation of absorption solution between said absorber and said generator, means for conveying refrigerant vapor from said generator to said condenser, means for conveying refrigerant liquid upwardly from said condenser to said evaporator, and an air circulator arranged to circulate air in said food compartment over said evaporator.

25. In a refrigerator, a cabinet structure including an insulated food compartment and a mechanism chamber arranged for flow of cooling air therethrough, an absorption refrigerating apparatus associated with said cabinet structure including an evaporator in the lower part of said compartment, an air cooled absorber and an air cooled condenser in said chamber below said food compartment, a generator in said chamber, means providing for circulation of inert gas between said absorber and said evaporator, means providing for circulation of absorption solution between said absorber and said generator, means for conveying refrigerant vapor from said generator to said condenser, means for conveying refrigerant liquid upwardly from said condenser to said evaporator, an air circulator arranged to circulate air in said food compartment over said evaporator, and electrical means for operating said air circulator arranged out of contact with the air in said food compartment.

26. In a refrigerator, a cabinet structure including an insulated food compartment and a mechanism chamber arranged for flow of cooling air therethrough, an absorption refrigerating apparatus associated with said cabinet structure including an evaporator in said compartment, an air cooled absorber in said mechanism chamber, an air cooled condenser positioned below the upper wall of said cabinet structure and within the vertical projection of the horizontal dimensions of said insulated food compartment, a generator in said chamber, means providing for circulation of inert gas between said absorber and said evaporator, means providing for circulation of absorption solution between said absorber and said generator, means for conveying refrigerant vapor from said generator to said condenser, means for conveying refrigerant liquid from said condenser to said evaporator.

27. In a refrigerator, a cabinet including an open bottomed insulated element adapted to form the side and top walls of an insulated refrigerating chamber and a base and mechanism element removably supporting said first mentioned element and including an insulated panel arranged to interfit with said first mentioned element to form the lower wall thereof, a refrigerating mechanism associated with said base element including an evaporator positioned above said insulated panel, refrigerant vapor producing means and an air cooled heat rejecting element positioned in said base element underlying said panel, and means connecting said evaporator, said refrigerant vapor producing means and said heat rejecting element in circuit, said base element being constructed and arranged to support said refrigerating mechanism and said first mentioned element.

28. In a refrigerator; a cabinet structure comprising an insulated refrigerating chamber and a mechanism chamber underlying said refrigerating chamber, said mechanism chamber being open at the rear of said cabinet structure for egress of cooling air and at the bottom thereof for entrance of cooling air; an absorption refrigerating mechanism including a condenser, a generator, an absorber and an evaporator; means connecting said condenser, generator, absorber and evaporator in circuit; means supporting said generator, absorber and condenser in said mechanism chamber beneath said refrigerating chamber, said evaporator being positioned in said refrigerating chamber, said absorber comprising a tubular finned conduit arranged in the forward portion of said mechanism chamber, means to lift refrigerant liquid from said condenser to said evaporator, and said condenser comprising a tubular finned conduit positioned in said mechanism chamber rearwardly of said absorber.

29. In a refrigerator; a cabinet structure comprising an insulated refrigerating chamber and a

mechanism chamber underlying said refrigerating chamber, said mechanism chamber being open at the rear of said cabinet structure for egress of cooling air and at the bottom thereof for entrance of cooling air; an absorption refrigerating mechanism including a condenser, a generator, an absorber and an evaporator, means supporting said generator, absorber and condenser in said mechanism chamber beneath said refrigerating chamber, said evaporator being positioned in said refrigerating chamber above said absorber and said condenser; means connecting said condenser, generator, absorber and evaporator in circuit including means for elevating refrigerant liquid from said condenser to said evaporator; said absorber comprising a tubular finned conduit arranged in the forward portion of said mechanism chamber, said condenser comprising a tubular finned conduit positioned in said mechanism chamber rearwardly of said absorber, and said generator being positioned in said mechanism chamber at the rear portion thereof.

30. In a refrigerator; a cabinet structure including an insulated refrigerating compartment and a mechanism compartment, an absorption refrigerating apparatus associated with said cabinet structure comprising an evaporator in said refrigerating compartment, an air cooled absorber and an air cooled condenser in said mechanism chamber, a generator in said mechanism chamber, means connecting said generator and said absorber for circulation of absorption solution therebetween, means connecting said evaporator and said absorber for circulation of inert gas therebetween, means for conveying refrigerant vapor from said generator to said condenser, and means for lifting refrigerant liquid upwardly from said condenser to said evaporator, said condenser and said absorber being located adjacent the bottom portion of said cabinet structure.

ARNOLD D. SIEDLE.
